UNITED STATES PATENT OFFICE.

CARL F. FREDRIKSON, OF CHICAGO, ILLINOIS, ASSIGNOR TO HERBERT S. MILLS, OF CHICAGO, ILLINOIS.

ART OF ARRANGING MUSIC.

1,370,202.

Specification of Letters Patent.

Patented Mar. 1, 1921.

Application filed April 17, 1919. Serial No. 290,664.

To all whom it may concern:

Be it known that I, CARL F. FREDRIKSON, a citizen of the United States, residing at Chicago, in the county of Cook and State of Illinois, have invented a new and useful Improvement in the Art of Arranging Music, of which the following is a specification.

The present invention relates to the art of arranging music and more particularly as applied to a sequence of musical selections of variable style and length to be played by automatically operated musical instruments.

In utilizing automatically operated musical instruments, such as electrically operated violin and piano players of the type illustrated by the patents to H. K. Sandell, Nos. 807,871 and 1,045,444, wherein a perforated roll of paper or other thin sheet material is employed to actuate the instruments, it has become highly desirable that means be provided whereby a sequence of musical selections of selected styles and selected lengths, variable at the will of the operator, may be played. Thus, in coördinating such instruments with motion pictures, the selections played to accompany the various scenes or portions of the picture must be varied in style in accordance with the action or emotion depicted and in length with the duration of such action or emotion. The necessary character of the musical selections used and their proper length may readily be determined by an experimental run of the picture, noting the types and duration of the various portions thereof involving different actions and emotions. The sequence of these selections and their lengths will necessarily vary to accompany each picture. It has been found that the styles of the musical selections required may be standardized and fall into a relatively small number of groups, such as the march, the lyric waltz, fast dance music, slow dance music, popular song transcriptions, transcriptions of dramatic music and funeral music.

In adapting perforated sheet actuated automatic instruments to such coöordinated operation a number of expedients have hitherto been proposed. Thus it has been suggested that special rolls be cut to accompany each picture, containing the proper styles of selections of the proper duration in

a sequence following the changes in action and emotion in the picture. It has also been proposed that multiple sheet operating mechanism be utilized, whereby a plurality of perforated sheets producing different styles of music may be severally caused to actuate the mechanism of the instrument by an operator controlling the same. Such methods as have been proposed, however, are found to involve a considerable expense in the manufacture of special rolls or in maintaining a special operator for the instrument, or are unadaptable to the special requirements of an individual operator or type of audience.

In accordance with the present invention it has now been found that these various difficulties in utilizing sheet-operated musical instruments to accompany motion pictures may be obviated by providing sheet sections capable of producing various styles of music in various lengths and capable of being separably united in any desired sequence to produce a continuous sheet forming a suitable accompaniment for any specified picture. A library of sheet sections may be provided containing selections classified as to style of music and length of selection, and the operator selects at will therefrom selections of any desired style and length best adapted for the depicted action or emotion which it is to accompany. The selections in such a library may be supplemented, renewed or discarded at will and may be combined to provide a widely variable sequence of musical selections adaptable to accompany any picture and to the caprices of the audience.

The selected sheet sections are then separably united in the proper sequence, for example, as illustrated in the accompanying drawings, to form a continuous sheet which is wound upon a roll and placed in the instrument in the usual manner. The resulting sheet of music may then be played and rewound in the usual manner as though it were a unitary sheet. After need for the particular sequence of selections has passed, the various sections making up the sheet may be disassembled and returned to the library and may be reused whenever required.

trated means whereby the several sheet sections may be separably united in accordance with the present invention.

Figure 1 shows in plan view the contiguous interlocked ends of two sheet sections.

Fig. 2 shows the front end of a section, disassembled, and Fig. 3 shows the end of a section disassembled.

Referring more particularly to the drawings, the numerals 5 and 6 designate successive sections of perforated sheets adapted for use in an automatic instrument, preferably of the electrical type. The front end of each section is sharply cut away as shown in Fig. 2, to form a narrow neck 7, from which the tongues 8, 8 extend laterally in each direction. The rear end of each section is similarly cut away to form a neck 9, from which the tongues 10, 10 extend laterally in each direction. The tongues 8, 8 at the front ends of the sheet sections are slightly longer than the tongues 10, 10 of the rear ends of the sheet sections, for the purpose hereinafter set forth. The front ends of each section are likewise provided with slots 11, 11, spaced apart the width of the neck 9 formed on the rear ends of each section, and the rear ends of the sections are provided with slots 12, 12, spaced apart the width of the necks 7 formed on the front ends of the sections. Additional slots 13, 13 are provided laterally of the slots 12, 12. The ends of the sheets are preferably imperforate.

In assembling the sheet sections the front end 6 of a section is placed over the rear end 5 of the preceding section, as indicated in Fig. 1. (The arrow indicates the direction of motion of the assembled sheet as it travels over the tracker-board of the instrument.) The tongues 10, 10 on the rear end of the first sheet are passed through the slots 11, 11 to the upper side of the sheet. The tongues 8, 8 on the forward end of the following sheet are passed downwardly through slots 12, 12. These tongues 8, 8 are formed longer than the tongues 10, 10 in order that they may be passed through

slots 13, 13 to the upper side of the sheet to prevent their being torn or frayed by the tracker-board in passage thereover. The relative positions of the slots and tongues is such that on assembling them as shown in Fig. 1, the assembled sheets are locked against relative movement laterally or longitudinally. Each sheet section is formed with a forward end as illustrated by Fig. 2 and a rear end as illustrated by Fig. 3.

The selected sheet sections are interlocked in the above described manner to form a continuous sheet which is wound upon a roll and used in the instrument as a unitary sheet to accompany a picture. It is readily apparent that such assembled sheets may be used in other connections, such as to accompany plays, pantomimes, etc., presented by living actors.

Although I have described my invention in connection with certain specific details of the means involved therein, it is clearly apparent that it is not limited to such details except in so far as such limitations are set forth in the accompanying claims.

I claim:

1. The method of arranging the musical score of automatic instruments operated by perforated sheets to accompany predetermined scenic representations and to harmonize with the subject matter thereof, which consists in selecting sections of compositions to form a complete score of appropriate style and length, and consecutively uniting the same in proper sequence to form a unitary sheet.

2. The method of arranging the musical score of automatic instruments operated by perforated sheets to accompany predetermined scenic representations and to harmonize with the subject matter thereof, which consists in selecting sections of compositions to form a complete score of appropriate style and length, and separably and consecutively uniting the same in proper sequence to form a unitary sheet.

CARL F. FREDRIKSON.
